LOOM AND ACTUATION MEANS FOR
LOOM SHUTTLES

Antonio Longoria, Cleveland, Ohio

Application June 6, 1950, Serial No. 166,427

13 Claims. (Cl. 139—145)

1

This invention relates to looms, and especially to the particular type of actuation or throwing means provided for effecting the desired rapid transverse movement of the shuttle of the loom.

For many, many years, looms have been provided with shuttles that are moved or thrown across the loom in order to carry the weft, or pick thread of the material across the warp threads in the material being woven. It has been common practice for a great length of time to throw these shuttles across the loom by means of a wooden actuation or control arms or picker sticks, which are pivotally secured to side portions of the loom adjacent one end of the arm and with the free end of the arm being that which engages with the shuttle to move or throw same. The control arm has itself been actuated by an impact mechanism that engages with the control arm intermediate the free and pivoted ends thereof so that the control arm is given a violent or hammered type of actuation in order to obtain the desired high-speed movement to the loom shuttle. Obviously such impacts of the shuttle and the shuttle control arm have produced continual noise and vibration in previous types of looms so that in a factory where there is any number of looms, there has been so much noise, vibration and general disturbance that it has been very difficult for the workers to work efficiently. Furthermore, the great vibration and frequent jars have, together with the hammering type of shuttle operation of these machines, caused the machines to break down relatively frequently, so that looms have been quite expensive to maintain and keep in good operating condition. Heretofore weaving factories have required as many as two maintenance mechanics for every 20 to 25 looms in a given factory. Also, due to the excessive shock and the vibration and wear on machines of this type, the wooden picker sticks used usually last only about two to seven days and consequently are an expensive maintenance and replacement item.

It is the general object of the present invention to avoid the foregoing and other difficulties with and disadvantages of present types of looms, and to provide a loom which is characterized by the quiet, effective and substantially vibrationless and jar-free operation thereof.

Another object of the invention is to provide a drive for a shuttle in a loom which drive is efficient, sturdy, and easily controlled, and which avoids a hammer-type impact drive of the shuttle.

A further object of the invention is to provide a unitary control in a loom for shuttle operating

2

means positioned adjacent each lateral margin of the loom.

Another object of the invention is to use a set of spring members for actuation of a shuttle in a loom.

A further object of the invention is to provide adjustable, easily replaced coil springs in a loom for driving or throwing the shuttle of the loom, which springs can readily be compressed and locked in a compressed condition and released at a desired instance in the cycle of operation of the loom.

Yet another object of the invention is to provide a new type of a stop member in a loom for receiving the impact of the shuttle, which stop member can easily be adjusted to vary the resistance thereof and which can readily be provided with new stop means.

Another object of the invention is to provide a loom which has relatively low maintenance cost thereon, and which is substantially free from vibration and jars or impacts.

It is another object of the present invention to provide shuttle throwing and stopping means in a loom whereby the service life of a shuttle and the actuation means therefor are greatly increased over that obtained in previous types of looms.

The foregoing and other objects and advantages of the invention will be made more apparent as the specification proceeds.

For a better understanding of the present invention, attention is directed to the accompanying drawings which disclose one presently best known embodiment of the invention, and wherein.

Fig. 1 is an elevation, partially broken away, of a loom particularly showing the shuttle control means of the invention;

Fig. 2 is a sectional view taken on line 2—2 of Fig. 1 showing the drive means of the apparatus of the invention; and

Fig. 3 is an enlarged section taken on line 3—3 of Fig. 1;

Fig. 4 is an enlarged plan taken on line 4—4 of Fig. 1;

Fig. 5 is an enlarged section taken on line 5—5 of Fig. 4 of the shuttle contact means;

Fig. 6 is a vertical section, partially broken away and taken on line 6—6 of Fig. 4 of the spring drive means for the shuttle;

Figs. 7 and 8 are fragmentary vertical sections of the spring control means taken on lines 7—7 and 8—8, respectively, of Fig. 6; and

Fig. 9 is an enlarged fragmentary vertical section taken on line 9—9 of Fig. 4.

The present invention, broadly speaking, can be said to comprise the provision of drive means for a shuttle in a loom, wherein such drive means comprises a set of coil springs positioned adjacent each lateral margin of a loom, unitary drive means, spring compression means associated with each set of the springs and controlled by the unitary drive means for alternately compressing the sets of coil springs, lock means for retaining the coil springs in a compressed condition, a control arm associated with each set of coil springs for contacting the shuttle to throw same, and release means controlled by the unitary drive means for releasing the compressed sets of coil springs at desired instances in the cycle of operation of the loom.

In order to facilitate correlation between corresponding parts in the accompanying specification and drawings, corresponding numerals will be used to identify such parts in both the drawings and the specification.

Reference now should be had to the details of the structure shown in the accompanying drawing, and a loom is indicated in general by the numeral 1. This loom is not shown completely but only the portion of the loom associated with or relating to the movement of the shuttle across the loom is shown. Thus the portion of the loom illustrated includes a frame for the lay of the loom and indicated by the numeral 2. This frame 2 includes a pair of vertically extending supports 3 the lower ends of which are positioned by means of bushings or bearings 4 which themselves engage with support pins 5 positioned by and extending between housings 6. The frame 2 has control rods or links 7 secured to each of the supports 3 adjacent the upper portions thereof and these rods 7 connect to suitable means (not shown) by which the frame 2 can be oscillated with relation to the remainder of the loom to facilitate the desired weaving action in conformity with conventional practice.

Drive mechanism

The drive for the shuttle control means of the invention is shown as including a standard electric motor 8 which has a driven output shaft 9 that connects to and drives a driven or control shaft 10 by conventional means such as a plurality of gears 11 which form a speed reducer connection for driving the shaft 10. The shaft 10 is journaled in suitable bearings 12 at each end thereof. The shaft 10 has an eccentric 13 suitably secured thereto and a split collar 14 is carried by the eccentric 13 for relative rotation therebetween. The collar 14 has a connector rod or link 15 extending therefrom and it connects to a turnbuckle or connector sleeve 16 by a threaded engagement. The other end of the sleeve 16 has a similar connector rod 17 threadably engaged therewith and extending therefrom. This second connector rod 17 has a ball and socket joint connection with an arm 18 which extend rigidly from a control rod 19 the ends of which are suitably journaled in portions of the frame 2. The arm 18 is spaced only slightly from the support pins 5. Thus upon operation of the motor 8, the eccentric 13 is adapted to cause oscillation of the control rod 19. The lower end of the control rod 19 is shown suitably journaled in an extended portion 20 of the frame 2.

The upper end or portion of the control rod 19 has an actuating arm 21 suitably secured thereto and protruding therefrom and this arm 21 has a pivotal connection, by a bolt or similar

member 22, with a connector link 23. The link 23 has a pivotal engagement with a pusher rod or bar 24 that extends substantially the width of the frame 2. This pusher bar 24 is positioned by and is slidably received in positioning sleeves or brackets 25 that are suitably secured to portions of the frame 2 adjacent the supports 3 of the frame. The pusher bar 24 is positioned for sliding movement transversely of the loom 1 and this pusher bar is provided with reciprocating movement in desired time relationship to the operation of the rest of the loom. Such motion of the pusher bar is provided by the motor 8 by the mechanism described hereinbefore, and specifically, by the connector link 23. The bar 24 may be adjustable in length.

Spring shuttle actuation means

The spring mechanism of the invention is best shown in Figs. 6 through 9 of the drawings and it includes a pair of end plates 26 and 27 that are suitably secured to the frame 2 adjacent each marginal portion thereof with the plates 26 and 27 being positioned in spaced parallel relation to each other. A plurality of bearing rods 28 are suitably engaged with and extend between the pairs of end plates 26 and 27 by means of threaded studs 29 that extend therefrom through the end plates and have nuts 30 engaged therewith to provide a solid, unitary assembly of the bearing rods and end plates. A pusher plate, or compression control plate 31 is slidably engaged with each unit of bearing rods 28 for movement therealong. The drawings indicated that sleeves 32 may be welded or otherwise engaged with the pusher plates 31 and be in snug sliding engagement with the bearing rods 28 to position the plates 31 in a desired manner.

As an important feature of the invention, a plurality of coil springs are positioned in sets in association with each pair of end plates 26 and 27 whereby a large and controllable spring force can be produced by the apparatus of the invention for actuation or drive of the shuttle of the loom. The spring means provided are positioned by a plurality of positioning rods or tubes 33 that extend through each set of end plates 26 and 27 and which are positioned in parallel relation to each other and to the bearing rods 28. Each of these positioning tubes 33 normally receives a coil spring 34 thereon. Each of the pusher or control plates 31 is adapted to engage with corresponding ends of each of the coil springs 34 and, upon movement of the pusher plate 31 towards the end plate 26, compress the sets of coil springs 34. Movement of the pusher plate 31 is provided by means of the pusher bar 24 that extends through the end plates 27 and is partially positioned thereby. Each end of the pusher bar 24 is provided with a foot 35 that is adapted to contact the inner surface of each of the pusher plates 31 and effect movement thereof upon outward movement of that particular end of the pusher bar 24 and the foot 35 provided thereon that engages that particular pusher plate 31.

Normally it is necessary to lock the sets of coil springs 34 in compressed positions and suitable release means are provided for releasing the stored energy in such coil springs at any desired instance for shuttle actuation. These lock means are shown as comprising a lock arm 36, which has a substantially C-shaped end portion therein with a roller 37 being journaled in the end of the lock arm, which extends inwardly of the ap-

paratus from the end plate 26, by suitable positioning means. These positioning means may comprise a substantially U-shaped bracket 38 that is removably secured to the end plate 26 by nuts 39 and which serve to position the bracket 38 rigidly in the apparatus. The free end portion of the lock arm 36 may be beveled or slanted upwardly of the loom as at 36a in a direction extending inwardly of the loom whereby the lock arm 36 can readily be deflected upwardly of the loom, when desired, as hereinafter pointed out. Each of the pusher or control plates 31 has rigidly secured to the laterally outer surface thereof a lock arm 41 which has an upwardly turned end portion 42 on which a roller 43 is journaled in a conventional manner. The lock arms 36 and 41 are so positioned with relation to each other that upon compression action of the pusher plate 31 by being moved towards the end plate 26, the roller 43 will strike the roller 37 and end 36a of the lock arm 36 and deflect it upwardly up over the roller 43. It will be noted that the roller 43 is positioned vertically above the normal (lowest) position of the roller 37 whereby once the pusher plate 31 is moved sufficiently far across the bearing rods 28 to pass beyond the roller 37, such lock arms 36 and 41 will be in locked engagement until displaced with relation to each other by some externally applied force.

Downward movement of the control arm 36 can be limited by any conventional means such as a pin 100 that is suitably secured to and protrudes from a portion of the positioning bracket 38 or other fixed member. This control pin 100 is so positioned with relation to the control arm 36 that it limits downward movement thereof to a substantially horizontal position as shown in Fig. 6. With the control arm 36 in the position shown, the roller 37 is positioned slightly below the vertical position of the roller 43 but is free to raise up and drop down into engagement therewith. Release of the engaged rollers 37 and 43 can only be effected by a vertically upwardly directed force applied to the control arm 36 and such action necessitates a further slight compression of the set of coil springs 34, until the roller 37 is slightly vertically above the centerline of the roller 43 at which time a substantially instantaneous upward and release movement of the roller 37 will be immediately and automatically provided. The control or pusher plate 31 and associated means will immediately actuate the shuttle controlled by that portion of the apparatus when such pusher plate is released.

Any desired type of lock release mechanism may be provided in the loom 1 and Figs. 1 and 6 indicate that a release link 44 is positioned below each set of the springs 34 and it is pivotally secured to the frame 2 by means of a positioning link 45 that is pivotally carried by a lower portion of the frame 2 adjacent each lateral margin thereof. This release link 44 is fixedly secured intermediate its ends to the link 45 and the other end of the release link 44 is pivotally secured to a control rod 46 which extends transversely of the apparatus and has the second end thereof pivotally secured to an arm 47 which is fixedly secured to the control rod 19 and extends therefrom at substantial right angles thereto whereby this control arm 47 oscillates with the control rod 19 and the control rod 46 is moved like the pusher bar 24. Fig. 6 of the drawings clearly indicates that the upper end of the release link 44 is positioned immediately below the lock arm 36

so that upon reciprocation of the control rod 46, the upper end of this release link 44 is moved through an arc and it has sufficient vertical movement by reason of its pivoting about the fixed end of the positioning link 45 to effect an upward actuation of the lock arm 36 and release the engagement of rollers 37 and 43 whereby the pusher plate 31 is released and the shuttle is actuated, as hereinafter described.

10 A coil spring 48 or equivalent device is usually connected to the lower portion of the lock arm 36 by means of a wire 49 so that this lock arm is normally urged or pulled downwardly into its lowermost position. The coil spring 48 can be suitably engaged with the frame 2 or other securing member in any desired manner.

15 Each of the pusher plates 31 has a shuttle control arm or plate 50 suitably secured to the upper portion therefrom and extending across the loom 20 of the invention to a point in the path of a shuttle 51, of conventional construction, which is provided for being thrown or impelled or otherwise moved transversely of the loom 1 to deposit the pick thread in the material being woven. It

25 will be noted that the shuttle 51 has sharp points at each end thereof, and the point of the shuttle 51 is received on suitable cushioning means to stop the shuttle at each lateral margin of the loom. Such shuttle stopping means may include

30 a metal member, or sleeve 52, Fig. 5, which is secured by a cap screw 53 to an end portion of the control plate 50. The sleeve 52 receives therein a plurality of discs 54 which may be made from any kind of rubber, or rubber-like material, including synthetic rubbers and other discs 54a that may be made from rawhide. The resiliency or stiffness of each of the discs 54 may be varied as desired. These discs 54 and 54a are retained within the sleeve 52 by an apertured end cap 55

40 which has threaded engagement with an end portion of the sleeve 52 and which has a hole or aperture 56 in the end thereof to permit the end of the shuttle 51 to contact the exposed surface of the end disc 54a. Should it be desired to replace one of the discs, it can readily be done by merely removing the end cap 55 and inserting a different disc. The tension or compression set up on the discs 54 and 54a can readily be varied by loosening or tightening the cap, or by removing the cap 55 and inserting different width or thickness discs in the sleeve 52.

45 In some instances it is desirable to vary or adjust the compressional force set up in the shuttle control means of the invention so that an adjustable end or stop plate 57 usually is provided in the loom. One of the end plates 57 is slidably engaged with each set of the bearing rods 28 and has abutted thereagainst the ends of the coil springs 34 remote from the ends thereof engaged with the pusher plates 31. The adjustable end

50 plate has a conventional threaded bushing 58 or similar member suitably secured thereto and a threaded cap screw 59 or similar member engages the bushing 58 and protrudes through the end plate 26. The cap screw 59 has a head 60 provided thereon whereby rotation of the head can vary the relationship between the end or stop plate 57 and the associated end plate 26 so that the effective length provided in the spring control means can be varied to control the compression set up in the different coil springs when moving same into their compressed, or locked condition. Of course, the adjustable end plates 57 are movable with relation to the brackets 38 and the coil spring positioning tubes 33.

Vibration, or shock or impact in the loom of the invention is reduced by the provision of cushioning means for gradually stopping the movement of the pusher plates 31 after they have been individually released or shot across the limited space between the sets of end plates 26 and 27 when the lock means provided for the pusher plates have been released. Such cushioning means may comprise a plurality of discs 61, which may be made from rubber, or similar material and which are engaged with and positioned by the individual bearing rods 28. Spacer sleeves 62 are provided, usually to position the resilient discs 61 at desired positions on the bearing rods 28.

It will be appreciated that the positions of the control feet 35 provided for opposite ends of the pusher bar 24 will always be at opposite or diametrically opposed portions of operative cycles for the two different shuttle impelling means on opposite transverse sides of the loom of the invention. Likewise, the lock release means are always at opposite portions of an operative cycle whereby a unitary control means is provided for operating both shuttle impacting means of the invention. Thus a desired timed relationship can be set up between the cocking of each shuttle actuating mechanism and the release thereof, and the actions of the two shuttle actuating means are positively correlated in a desired time relationship by use of the common control rod 19.

As an auxiliary feature of the invention which facilitates changing coil springs used or replacing a damaged spring, a cover plate 63, Fig. 6 is associated with each end plate 26 on the outer surface thereof and is of a size to cover all of the ends of the positioning tubes 33. The cover plates 63 are held in position by any suitable means which may comprise the nuts 39 which aid in holding the brackets 38 in position. Hence upon removal of the nuts 39, the cover plates 63 can be removed and any desired tube 33 can be slid from engagement with the pair of end plates 26 and 27 between which it is positioned and in which such positioning tube is snugly but freely received. Similar cover plates 64 usually are associated with the end plates 27 and are retained therein by bolts 65 that are secured to the end plates 27.

The shuttle 51 strikes or is received in a conventional binder 66 that aids in stopping motion of the shuttle, and it moves across a conventional part of the loom. Tests in apparatus of the class described herein have indicated that shuttles striking the shuttle stopping means of the invention will rebound only a very small amount, such as $\frac{1}{8}$ to $\frac{1}{4}$ ". Furthermore, by the resilient stopping and impact transmitting means of the invention, shuttle life is greatly enhanced.

It will be appreciated that the control rod 46 may have an adjustable connection with the control link 44 for regulating movement of this control link. If desired, other suitable guide means may be provided for the control link or rods 46 and be carried by the frame 2 or brackets associated therewith.

In the apparatus shown, the shaft 10 illustrates the conventional drive shaft of a loom and the means provided in this instance for driving the shaft 10 usually will not be present in the apparatus being replaced by the conventional loom driving means. The particular relationship of the eccentric 13 to the shaft 10 controls the timing of the apparatus in combination with the specific positions of the control arms 21 and 47 on

the control rod 19 and the particular relationship with each other and the means controlled thereby.

In a modification of the invention, the rubber discs or sleeves 61 may be replaced by means of an air cylinder which is secured to the end plates 27 and receive therein a plunger which is secured to and carried by each of the pusher plates 31. A suitable valve is provided in the end of the cylinder remote from the pusher plates 31 whereby a controllable release action is secured on air received within such air cylinder. On cocking or compressive movement of the pusher plates 31, air is freely drawn into the air cylinder through the control valve provided therefor.

It will be appreciated that the foot portion 35 provided on each end of the control or pusher rod 24 may be made from any desired material and may have a resilient face portion to lessen the noise and impact of contact with the surface of the pusher plate 31. After the pusher rod had moved the pusher plate 31 into a locked position, the continued movement of the pusher plate will be that of a return reciprocation movement and the foot portion 35 will be disengaged with that specific pusher plate and the corresponding foot portion 35 upon the opposite margin of the apparatus will engage its pusher plate to start a cocking action on that portion of the apparatus.

It may be desirable in some instances to use some kind of a delayed timer or electrical release means for releasing the cocked sets of coil springs for shuttle actuation.

It will be appreciated that the remaining part of the apparatus not specifically described herein will conform in general to standard loom construction.

From the foregoing, it should be seen that a sturdy, effective, easily adjusted type of spring actuating mechanism has been provided for the shuttle control means of the invention. These means have a cushioned stopping action on the control or pusher plate and associated means and the actuating or cocking means of the invention are easily and readily engageable with and disengageable from the pusher plates of the apparatus so that a positive compression or cocking action is obtained by the apparatus. A relatively, inexpensive, uncomplicated actuation device is provided for the shuttle and novel impact means start and stop the shuttle's movement. In view of the foregoing, it is submitted that the objects of the invention have been realized.

While one complete embodiment of the invention has been disclosed herein, it will be appreciated that modification of this particular embodiment of the invention may be resorted to without departing from the scope of the invention, as defined by the appended claims.

Having thus described my invention what I claim is:

1. In a loom, a frame, a pair of end plates secured to spaced portions of said frame, a plurality of bearing rods secured to and extending between said end plates in parallel relation to each other, a plurality of carrier sleeves slidably carried on said bearing rods, a compression control plate secured to said carrier sleeves for movement along said bearing rods, a plurality of positioning tubes extending between said end plates in spaced parallel relation to each other and to said bearing rods, a coil spring received on each of said tubes intermediate one said end plate and said control plate, a stop plate posi-

tioned intermediate corresponding ends of said springs and said one end plate, means for adjusting said stop plate to vary the positions of said springs, an arm secured to said control plate and extending therefrom to contact and throw a shuttle on release of said control plate, means for moving said control plate to compress said springs, and means for releasing said control plate.

2. In a loom, a frame, a pair of end plates secured to spaced portions of said frame, a plurality of bearing rods secured to and extending between said end plates in parallel relation to each other, a control plate slidably carried by said bearing rods, a plurality of positioning members extending between said end plates in spaced parallel relation to each other and to said bearing rods, coil spring means received on said positioning members intermediate one said end plate and said control plate, an arm secured to said control plate and extending therefrom to contact and throw a shuttle on release of said control plate, means for moving said control plate to compress said springs, and means for releasing said control plate.

3. In a loom, a frame, a pair of opposed end plates secured to spaced portions of said frame, a plurality of bearing rods secured to and extending between said end plates in parallel relation to each other, a compression control plate slidably carried by said bearing rods, a plurality of positioning tubes extending between said end plates in spaced parallel relation to each other and to said bearing rods, a coil spring received on each of said tubes intermediate one said end plate and said control plate, a stop plate positioned intermediate corresponding ends of said springs and said one end plate, means for adjusting said stop plate to vary the positions of said springs, means for moving said control plate to compress said springs, means for locking said control plate in a position with said springs in compressed condition, and means for releasing said control plate.

4. In a loom, a frame, a pair of opposed end plates secured to spaced portions of said frame, a plurality of bearing rods secured to and extending between said end plates in parallel relation to each other, a compression control plate slidably carried by said bearing rods, a plurality of positioning tubes extending between said end plates in spaced parallel relation to each other and to said bearing rods, a coil spring received on each of said tubes intermediate one said end plate and said control plate, means for moving said control plate to compress said springs, means for locking said control plate in a position with said springs in compressed condition, and means for releasing said control plate.

5. A loom as in claim 4 wherein said lock means comprise one member pivotally secured to said frame, and one member carried by said control plate and engageable with said one member on said frame when said springs are compressed a desired amount.

6. In a loom, a frame, a continuously rotated driven member, a control rod, means connecting said driven member to said control rod to oscillate same, a set of coil springs positioned in parallel aligned relation, a compression control plate at one end of said coil springs, a stop plate at the other ends of said springs, means connected between said control rod and said control plate for moving said control plate to compress said springs, means carried by said

control plate and said frame for locking said springs in compressed form independently of the shuttle, and means operatively positioned between said lock means and said control rod to release said compressed springs in predetermined time relation to the compression of said springs.

7. In a loom, a continuously driven member, a control rod, means connecting said driven member to said control rod to oscillate same, a set of coil springs positioned in parallel aligned relation, a control plate at one end of said coil springs, a stop plate positioned at the other end of said coil springs, automatically engageable lock means operatively associated with said control plate and said stop plate to engage and retain said coil springs in compressed condition, and means connected between said control rod and said control plate for moving said control plate to compress said springs and engage said lock means.

8. In a loom having a shuttle movable there-across, coil spring means, an arm connected to said spring means for throwing a shuttle across the loom, means positioned for movement axially of said spring means for compressing said spring means, means for locking said spring means operatively associated with and at least partially carried by said first means in compressed condition, means for releasing the spring lock means at desired instances in the operation of the loom to effect a throw of the shuttle thereof, and unitary control means for said spring compressing means and said release means.

9. In a loom having a shuttle movable there-across, a plurality of coil spring means for throwing a shuttle across the loom, means for compressing the spring means as a unit, means for varying the compression of the spring means when completely compressed, means for locking the spring means in compressed condition, unitary means for securing corresponding ends of all of said spring means in position, individual means associated with each of said spring means to permit individual removal of each of said spring means when said unitary means is removed, and means for releasing the spring lock means at desired instances in the operation of the loom to effect a throw of the shuttle thereof.

10. Apparatus as in claim 6 wherein a set of compression springs, control plates and lock means are provided on opposite sides of a loom and link means connect said control rod to both of said lock means, and other link means connect said control rod to both of said control plates.

11. In an apparatus as in claim 3, shock absorbing means carried by said bearing rods adjacent the second of said end plates to cushion the termination of movement of said control plate on release thereof.

12. Apparatus as in claim 3, wherein said positioning tubes are retained in engagement with said end plates by cover plates secured to the outer surfaces of each of said end plates.

13. In a loom having a shuttle movable there-across, spring means for throwing a shuttle across the loom, means for compressing the spring means, means carried by said compressing means for locking the spring means in compressed condition, means for releasing the spring lock means at desired intervals in the operation of the loom to effect a throw of the shuttle thereof, a pusher plate associated with said compressing means and movable by said spring means upon release thereof from compressed condition,

11

and a plurality of resilient discs forming a stop for said contact plate at the end of its released spring movement.
